T. BORGAN

AEROPLANE CONSTRUCTION

Filed Nov. 20, 1925

UNITED STATES PATENT OFFICE.

THORALF BORGAN, OF BROOKLYN, NEW YORK.

AEROPLANE CONSTRUCTION.

Application filed November 20, 1925. Serial No. 70,392.

This invention relates to aeroplanes and has for its object the provision of a device in which the elevators are located in close association with the propeller and at the rear of the propeller so that when they are operated simultaneously the aeroplane may be elevated or lowered or when actuated independently of each other the aeroplane may be banked when rounding corners.

10 A further object of the invention is the provision of an aeroplane having an extended lifting surface which is composed of a plurality of longitudinally disposed spaced wires which are adapted to support a plurality of sections of thin metal strips having laterally projecting lugs engaging around the wires.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

20 Figure 1 is a plan view of an aeroplane constructed in accordance with the principles of my invention.

Figure 2 is a longitudinal side view of the aeroplane.

25 Figure 3 is a longitudinal vertical section of the aeroplane.

Figure 4 is a transverse vertical section taken along the line 4—4 of Figure 1.

30 Figure 5 is an enlarged vertical section taken along the line 5—5 of Figure 1.

Figure 6 is an enlarged fragmentary plan view of the main supporting surface.

35 Figure 7 is a section of the supporting surface shown in Figure 6 and taken along the line 7—7 of Figure 6.

Referring more particularly to the drawings, 10 designates the fuselage of an aeroplane which is adapted to support the engines 11 and 12 connected by means of 40 clutches to a drive shaft 13 carried by bearings 14. At the forward end of the shaft is rigidly secured a propeller 15. The forward end of the fuselage is provided with a cockpit having openings 16 and 17 for the

55 accommodation of the operators of the aeroplane. The fuselage is carried by means of the running gears 18 and 19.

Secured rigidly in any approved manner to the body 10 are a pair of planes 20 and 21 at the rear end of the machine. These 60 planes extend transversely of the body and are connected together at their ends as shown at 22 so that the pair of planes on opposite sides of the body are substantially V-shaped. A rudder 23 is mounted at the 65 rear of the machine and in aline with the longitudinal axis of the same. This rudder is provided with arms 24 connected to cables 25 which are carried forwardly to a point adjacent the seat of the aviator. At the forward end of the aeroplane and in advance of the opening 16 is mounted a shaft 27 which passes through the body 10 and is supported in bearings carried by said body.

70 Rotatably mounted on the shaft 27 are a 75 pair of elevators 28 and 29, an elevator being located on each side of the body. The elevator 29 is provided with a pair of diametrically disposed arms 30 and 31 to the ends of which is connected a cable 32. This cable 80 is entrained over a pulley 33 mounted on a shaft 34 which is operated by a control stick 35. The elevator 28 is likewise provided with a pair of arms similar to the arms 30 and 31 of the elevator 29, to the ends of 85 which is connected a cable 36 which is trained over a pulley 37 carried by a shaft. This shaft is operated by a stick 38.

As shown in Figure 1 sticks 35 and 38 are 90 located in spaced relation and adjacent the forward seat and adjacent the opening 16. The outer ends of the shaft 27 is braced by wires 39 and 40 which extend from a sleeve 41 at each end of the shaft and inwardly in the V-shaped formation and is connected as 95 shown at 42 to the body member 10. It will be seen by the separate control sticks 35 and 38 that both of the elevators 28 and 29 may be rocked simultaneously or independently of each other. Located in a horizontal 100 plane and passing substantially through the longitudinal axis of the body 10 is a supporting plane generally designated by the numeral 45. This supporting plane is composed of a supporting frame made of longitudinal wires 46. A pair of reinforcing wires 47 extend from a transverse bar 48 to the outer connected ends of the planes 20

and 21 as shown at 49. Turn buckles 47^a incorporated in the wires 47 and 50 are adapted to adjust the tension on said wires.

Reinforcing wires 50 which support the rear ends of the wires 46 extend from the outer connected ends 22 of the planes 20 and 21 as shown at 51 to the rear end of the body as shown at 52. The longitudinal wires 46 decrease in length from the body 10 outwardly in spaced relation upon opposite sides of the body and are connected to the wires 47 and 50 in any approved manner, the connection being such that the wires 46 are located substantially in the same 15 plane with the wires 47 and 50.

The supporting surface is formed of thin strips 53 formed from metal sheets. These strips extend longitudinally of the supporting surface and are provided with a plurality of lugs 54 projecting laterally from opposite sides of the strips and these lugs as shown in Figure 7 are bent downwardly and curved around the wires 46 in embracing relation with the wires 46.

25 In the operation of the plane the rudder 23 as is usual is controlled by the cables 25 from the point of vantage adjacent the seat of the aviator. The elevators 28 and 29 which are located directly at the rear 30 of the propeller 15 are oscillated through an arc of a circle simultaneously for causing the plane to be elevated or lowered. Since the planes are operated independently through the levers of the control sticks 35 and 38 either one may be operated for banking the plane. Due to the fact that the controls 28 and 29 are located directly at the rear of the propeller the air thrust of the propeller used in combination with the 40 disposition of said controls will be more effective for controlling the various positions of the plane than where the propeller is located at some distance from the controls as is ordinarily shown in the types of 45 planes now in use.

What I claim is:—

1. In an aeroplane, a lifting surface composed of a plurality of longitudinally disposed wires, other wires defining the periphery of the lifting surface, the longitudinally disposed wires being rigidly connected at their ends to the second mentioned wires, and strips of sheet metal disposed longitudinally and connected to the longitudinally disposed wires.

2. In an aeroplane, a lifting surface comprising a plurality of longitudinally disposed wires and a plurality of strips of sheet metal supported by the wires, said strips of metal having lugs projecting laterally from its opposite sides and bent around adjacent strands of wire.

3. In an aeroplane, a longitudinally dis-

posed body, planes extending transversely of the body adjacent one end, a lifting surface passing between the planes, said lifting surface comprising wires defining the boundaries of the lifting surface, and extending from the opposite ends of the planes towards the rear and front of the body and connected thereto, longitudinally spaced wires having their ends connected to the boundary wires, and strips of sheet metal connected to the longitudinally disposed wires.

4. In an aeroplane, a longitudinally disposed body, planes extending transversely of the body adjacent one end, a lifting surface passing between the planes, said lifting surface comprising wires defining the boundaries of the lifting surface and extending from the opposite ends of the planes towards the rear and front of the body and connected thereto, longitudinally spaced wires having their ends connected to the boundary wires, and strips of sheet metal connected to the longitudinally disposed wires, said strips of metal having lugs projecting laterally from the opposite edges and bent around the longitudinally disposed wires adjacent the longitudinal edges of the strips.

5. In an aeroplane, a longitudinally disposed body, planes extending transversely of the body adjacent one end, a lifting surface passing between the planes, said lifting surface comprising wires defining the boundaries of the lifting surface and extending from the opposite ends of the planes toward the rear and front of the body and connected thereto, longitudinally spaced wires having their ends connected to the boundary wires, and strips of sheet metal connected to the longitudinally disposed wires, said strips of metal having lugs projecting laterally from the opposite edges and bent around the longitudinally disposed wires adjacent the longitudinal edges of the strips, said lugs being located in spaced relation and staggered with respect to lugs on an adjacent strip so that the lugs of one strip when embracing a wire will neatly fit between the pair of lugs on an adjacent strip which are bent around the same wire.

6. In an aeroplane, a lifting surface composed of a plurality of longitudinally disposed wires, other wires defining the periphery of the lifting surface, the longitudinally disposed wires being rigidly connected at their ends to the second mentioned wires, and strips of sheet metal disposed longitudinally and connected to the longitudinally disposed wires, the second mentioned wires being provided with means for creating a tension thereon.

THORALF BORGAN.
